W. S. Franklin - Design -

J. A. Bailly, of Philadelphia, Penna.

Letter Patent No. 2184-Dated June 18-1865.

Design for a Statuette of Abraham Lincoln.

The schedule referred to in these Letter Patent and making part of the same.

To all whom it may concern:

Be it known that I, J. A. Bailly, of the City of Philadelphia, and State of Pennsylvania, have originated and designed a Statuette of Abraham Lincoln, late President of the United States of North America, of which the following is a full, clear and exact description reference being had to the accompanying drawings making a part of this specification.

This Statuette "as a Design is represented in citizens dress, a frock dress coat, vest and long pants, extending to the feet that are covered with boots. The right hand (exhibiting the four fingers in front) rests in an easy position on the upper part of the leg, with the right foot in front. The statuette or figure is supported on the left by a post representing a "Fasces" or bundle of rods, tied together across which the National Emblem hangs in folds. The left hand is clasped on the top of the "Fasces". The statuette stands upon a square block or base, and the whole is intended to be made of any material or composition, whether carved, moulded or cast.

Therefore, what I claim as my invention and production is the Statuette of Abraham Lincoln, as shown and described.
